CLAIM

We claim the ornamental design for a self-propelled agricultural machine, as shown and described.

DESCRIPTION

FIG. 1 is a right side view of a self-propelled agricultural machine showing our new design.

FIG. 2 is a left side view thereof.

FIG. 3 is a front view thereof.

FIG. 4 is a rear view thereof; and,

FIG. 5 is a top view thereof.

The ornamental design which is claimed is shown in solid lines in the drawings. Broken lines, if present in the drawings, are for illustrative purposes only and form no part of the claimed design.
